(57) **CLAIM**

The ornamental design for a vehicle frame rail, as shown and described.

DESCRIPTION

FIG. 1 is a perspective view of a vehicle frame rail according to our new design;

FIG. 2 is another perspective view of the vehicle frame rail shown in FIG. 1;

FIG. 3 is a right side elevation view of the vehicle frame rail shown in FIG. 1;

FIG. 4 is a left side elevation view of the vehicle frame rail shown in FIG. 1;

FIG. 5 is a top plan view of the vehicle frame rail shown in FIG. 1;

FIG. 6 is a bottom plan view of the vehicle frame rail shown in FIG. 1;

FIG. 7 is a front elevation view of the vehicle frame rail shown in FIG. 1; and,

FIG. 8 is a rear elevation view of the vehicle frame rail shown in FIG. 1.

The broken lines shown herein are for illustrative purposes only and form no part of the claimed design.
